UNITED STATES PATENT OFFICE.

JOSEPH FRALING, OF BEMIDJI, MINNESOTA.

MATCH LIGHTER.

Application filed February 4, 1924. Serial No. 690,521.

To all whom it may concern:

Be it known that I, JOSEPH FRALING, a citizen of the United States, residing at Bemidji, in the county of Beltrami and State of Minnesota, have invented a new and useful Match Lighter, of which the following is a specification.

This invention aims to provide a match lighter having a novel form of element along which the match may be moved when it is being struck. Another object of the invention is to provide novel means for holding the match in operative relation to the striking edge.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown, can be made without departing from the spirit of the invention.

In the accompanying drawings:—

Figure 1 shows in top plan, a device constructed in accordance with the invention; Figure 2 is a longitudinal section; Figure 3 is a cross section.

The device comprises a body 1, preferably in the form of a plate provided at its ends with holes 2 adapted to receive the securing elements (not shown), whereby the body 1 may be attached to a support of any kind. The body-plate 1 has a longitudinal opening 3 and in the formation of the opening 3, outwardly extending converging flanges 4 are fashioned along the edges of the opening. The edges of the flanges 4 are spaced apart at

such a distance that when a match is drawn along the flanges 4, in contact with both of them, the match will be lighted, although as hereinafter claimed, the match may be lighted by contact with but one of the flanges 4. Longitudinal guide ribs 5 are struck from the body 1 and are located parallel to the flange 4. The guide ribs 5 are disposed on opposite sides of the opening 3 and outwardly of the flanges 4. The guide ribs 5 are spaced at such a distance from the flanges 4 that, when a match is drawn along one of ribs 5, the head of the match will be in contact with one of the flanges 4 as shown in dotted line in Figure 3. The construction of the device is such that it will light a match readily, the match always being in contact with both of the flanges 4 or with one of the flanges and the corresponding rib 5.

I claim:

1. A match scratcher comprising a plate-like body having flanges struck outwardly therefrom and provided with free edges, the distance between the free edges of the flanges being such that when a match head is drawn along said edges, the head will engage both of said edges.

2. A match scratcher constructed as set forth in claim 1, and further characterized by the provision of guide ribs on the body, outwardly of the flanges, the distance between each rib and the edge of the corresponding flanges being such that when a match is drawn along the rib, the match will be in contact with the edge of the flange.

In testimony that I claim the foregoing as my own, I have hereto affixed my signature in the presence of two witnesses.

JOSEPH FRALING.
